(57) **CLAIM**

The ornamental design for a faucet, as shown and described.

DESCRIPTION

In a preferred embodiment, the nature of this product is as a plumbing fixture in the form of a faucet for washing various items and/or body parts.

FIG. 1 is a left, top, front perspective view of a faucet embodying our new design;

FIG. 2 is a front elevational view thereof;

FIG. 3 is a top plan view thereof;

FIG. 4 is a left side elevational view thereof; the right side elevational view thereof being a mirror image of the left side shown;

FIG. 5 is a rear elevational view thereof; and,

FIG. 6 is a bottom plan view thereof.

The broken line representation of a window opening in FIGS. 1, 2 and 4, sensors in FIGS. 1 and 2, a spout opening in FIGS. 2 and 6, and a bottom opening in FIG. 6 is for the purpose of illustration only, and form no part of the claimed design.
